UNITED STATES PATENT OFFICE

109,042

DESIGN FOR A MATCH BOX HOLDER

Patricia Graves, New York, N. Y.

Application January 14, 1938, Serial No. 74,309

Term of patent 7 years

To all whom it may concern:

Be it known that I, Patricia Graves, a citizen of the United States and a resident of New York, city, county, and State of New York, have invented a new, original, and ornamental Design for a Match Box Holder, of which the following is a specification, reference being had to the accompanying drawing, forming a part thereof.

The two opposite faces, front and rear, and the two opposite side faces are identical.

I claim:

The ornamental design for a match box holder, as shown.

PATRICIA GRAVES.
